ATTORNEY

UNITED STATES PATENT OFFICE

GUSTAV WOITHE, OF NEW YORK, N. Y.

ARTICLE SAFE

Application filed February 6, 1931. Serial No. 513,932.

This invention relates to safes in general, and particularly to article receiving and theft preventing devices.

One of the prime objects of this invention is to provide a receiving device into which articles may be placed from without, and from which such articles may be removed only from within.

Another object of my invention is to provide a device of this kind which may be readily secured to existing doors of residences or apartments, or which can be built into walls when new dwellings are being erected.

Another object of my invention is to provide an article safe so arranged that the article itself functions, not by its weight, but through its bulk as actuating means for operating the locking means of one of its closures intended to be inaccessible after the article is placed into the safe.

The foregoing and still further objects will become more fully apparent from the following description and the accompanying drawing, forming part of my disclosure in one of the many possible forms, but by no means intended to limit my invention to the actual showing, and in which—

Fig. 1 illustrates a partial diagrammatical elevation of a door to which my device is attached;

Fig. 2 is a partial cross sectional view taken on lines 2—2 of Fig. 1;

Fig. 3 is a partial cross sectional view taken on lines 3—3 of Fig. 1;

Fig. 4 is a top view of my device, partially broken away, showing the interior arrangement of the casing;

Fig. 5 is an elevation of my device with a portion of its attaching flange removed;

Fig. 6 is an enlarged detail cross sectional view, taken on lines 6—6 of Fig. 4, showing the automatic locking arrangement for the outwardly opening closure of my device;

Fig. 7 is a partial side elevation of the outer closure;

Fig. 8 is an enlarged detail view of a closure detent;

Fig. 9 is a partial detail side elevation of the outer door locking arrangement, and

Fig. 10 is a diagrammatical plan view in

cross section of door adjoining walls of a dwelling, showing the arrangement of my device.

Referring to Figs. 1, 2 and 3, a door 10 is illustrated having lower panel 11, to the rear or inner face of which is secured safe casing 12 provided with an inwardly opening closure or door 13. The latter is provided with an externally operable latch or lock 14 of any desired construction and is hinged to casing 12 at 15. This closure can be opened only from within door 10.

Forming either an extension or a separate part of the casing is a portion 16 adapted to project through an opening cut into panel 11 to which latter it is attached by means of flanges or frames clearly seen at 17 in Figs. 4, 5, 6 and 8. This portion 16 communicates with the interior of casing 12 and is provided with an outwardly opening closure or door 18 hinged to frame 17 at 19.

Closure or door 18 is provided with an externally operable locking device 20 (see Fig. 9) which may be of any desired construction, but in the form shown consists of a hand knob secured to pin 21 at one end, while the other end of the pin terminates in a latch 22 adapted to engage a slot provided in extension 16. Besides the externally operable locking device 20 there is provided with this closure an internally arranged locking arrangement clearly illustrated at Fig. 6.

It comprises upper and lower detents 23 and 24 slidably mounted within guides 25 and comprising directly actuated elements 26 and trailing or follow-up elements 27 interconnected by means of springs 28. These detent elements or members are in slidable engagement with one another and the trailing members 27 have their extreme ends tapered as shown at 29.

Rotatably mounted upon pin 21 is a disk 30 (see Figs. 6 and 7) with which are operatively connected detent actuating levers 31 and 32 engaging the near ends of detent members 26. Another connecting lever 33 is secured at 34 to the disk. The lever connections 34 and 35 of disk 30 are diagonally opposite one another and when disk 30 is turned in right hand direction (by lever 33) the de-

tent members 26 are forced out. This outward movement of lever connections and detents is indicated in broken lines in Fig. 6.

Secured also to outer door 18 is a double bearing 36, serving as guide for plunger 37, which latter extends from a horizontal article receiving platform 38. A coil spring 39 resting upon the upper surface of guide bearing 36 keeps platform 38 normally in position shown in full line in Fig. 6. Plunger 37 is provided with a slot 40 in which is operatively engaged actuating lever 41 pivoted at 42 and operatively connected at 43 with connecting arm or lever 33.

15 The moment platform 38 is depressed to its broken line position, the plunger engaging end of lever 41 will be forced downwards while its other end 43 is forced upwards. This upward movement is transmitted 20 through connecting rod 33 to disk 30 which is turned in clockwise direction and causes the movement of detent levers 31 and 32 from one another. The movement of levers 31 and 32 forces detents 23 and 24 to assume their 25 locking position, shown in broken lines. The moment platform 38 is released, all levers and the detents revert to their normal, full line and non-locking state. It is obvious, however, that the outwardly operable latch 20 30 functions independently from the internal locking arrangement.

From Figs. 6 and 7 it will be evident, that attached to door 18 are, what I term stationary or relatively fixed article engaging members 44, 45 and 46. Member 44 is truly fixed for the height of a quart milk bottle, while members 45 and 46 are pivoted and arranged at different heights for variously sized bottles. Their pivotal attachment is so arranged 40 as not to interfere with the placing of containers upon platform 38 when the members are not in use, as shown in full lines. Each of the pivoted members is provided with a brace or stop 47 adapted to bear against the inner door surface and serves as limiting means for the members when in use.

When any article, as for instance a bottle, a box or any other container is interposed between platform 38 and any one of the 50 members 44, 45 and 46, so that a pressure is exerted against the platform, which is thereby forced downwards, the movement causes the heretofore normally positioned locking arrangement to assume its broken line locking position. At such position detent trailing elements 27 are projected outwards and beyond the upper and lower ends of the door opening provided in frame 17. The door, yet open, as shown in broken lines at 55 Fig. 4, would not close, were it not for the inclined or tapered end 29 of trailing elements 27 and the yieldable spring suspensions 28 holding the two detent elements together. Due to the latter suspensions and the slanting edges of elements 27, the latter are tem-

porarily depressed by the edges of frame 17 and, having passed them, revert to their locking position, as seen in Fig. 8. At that position it is impossible to open the outer door 18, unless forced. The moment, however, the bottle pressing against platform 38 is removed from within the casing, door 18 is made accessible again from without.

From Fig. 4 it will be observed that the casing or safe may be filled with three bottles before the last or fourth bottle is interposed between platform 38 and any one of the three engaging members 44, 45 or 46. In order to prevent damage or turning over of the bottles while in the safe and during opening and closing of the dwelling door, a cushioning arrangement of any convenient design indicated at 48 in Fig. 4 may be provided.

In new dwellings my device may be secured within the walls as illustrated in Fig. 85 10, in which case the outer closure 49 is preferably placed next to the opening of the dwelling door and the inwardly opening closure 50 is arranged flush with the dividing wall. However any other arrangement of 90 the safe and its placement in the walls may be resorted to.

While I have shown specific constructions of my device, it is obvious that variations and improvements necessitated through its employment in different ways may be resorted to, and I therefore reserve for myself the right to make changes and improvements therein, without departing from the broad scope of my idea.

I claim:—

1. A milk bottle safe, adapted to be associated with doors or walls of a building, comprising in combination, a casing having a relatively small, sidewise opening door and a relatively large, bottle removal door, both doors provided with externally operable closing devices, said casing adapted to receive a plurality of milk bottles inserted through said small door and removable only through the large door, cushioning means for preventing damage to or fall of the bottles provided within the casing, automatic internal locking means provided with said small door and comprising upper and lower lever actuated 105 detents composed of directly operated and spring induced snap trailing members, relatively fixed and yieldable bottle engaging means secured to the small door, the latter means comprising a spring controlled bottle receiving platform, a lever connected therewith and with said locking means, said fixed engaging means adapted to engage the top of a milk bottle, said yieldable engaging means adapted to be depressed when a bottle 115 is placed between its platform and said fixed engaging means, thereby actuating said lever, the latter causing said locking means to assume its locking position, said spring induced snap trailing members of the detents 120 125 130

adapted to facilitate their temporary yielding from and their reverting to their locking position when the small door is closed.

2. An article safe, adapted to be associated with existing doors or walls of a building, comprising in combination, an articles-receiving casing adapted to be attached to the inside of a door or wall, such door or wall provided with an opening, said casing having a small outwardly swinging closure, adapted to occupy the opening in the door or wall, and an inwardly swinging large closure, said small closure adapted to facilitate the insertion of articles into the casing from without, said large closure adapted to facilitate the removal of articles from within, said small closure provided with a normally uncocked, automatic locking mechanism, the latter having means for facilitating the insertion of a single article and means whereby said article may cock said mechanism to its operative position, so that, when the closure is swung shut, said mechanism will lock the closure, said means for facilitating the insertion of an article and cocking said mechanism comprising a fixed and a yieldable platform mounted on the small closure, the former platform serving as fixed abutment for one end of the article, said yieldable platform serving as abutment for the other article end, said latter platform controlling the cocking operation of said locking mechanism.

In testimony whereof he herewith affixes
35 his signature.

GUSTAV WOITHE.
